POT TYPE BURNER FOR LIQUID FUEL

William C. Roberts, Detroit, Mich., assignor to
 Bone Tool & Gauge Company, Detroit, Mich., a
 corporation of Michigan

Application February 12, 1948, Serial No. 7,776

7 Claims. (Cl. 158—91)

1

This invention relates to burners and more particularly to an improved pot type burner for liquid fuel.

Heretofore many burners of this type have been designed and manufactured but these burners have been relatively inefficient, mainly due to improper introduction of the primary air necessary for efficient combustion, incomplete and slow vaporization of the liquid fuel and the formation of carbon deposits on the passage or passages through which the fuel flows into the combustion chamber.

It is therefore an object of this invention to provide a pot type liquid fuel burner of relatively simple and economical construction comprising only two major parts preferably castings.

It is a further object of this invention to provide a liquid fuel burner in which the fuel inlet passage is shielded from the actual combustion chamber in order to prevent formation of carbon deposits therein and in which the fuel is introduced into the combustion chamber through a plurality of passages, which passages may also serve for the introduction of primary air, thus resulting in a faster and more efficient vaporization of the fuel due to the flow of air over a moving body of the fuel.

It is a further object of this invention to provide a liquid fuel burner in which the fuel is supplied to the combustion chamber in a relatively thin film spread over a large area which permits the fuel to be quickly heated to a relatively high temperature, thus increasing the rate of vaporization.

It is a further object of the invention to provide a liquid fuel burner in which the primary air passages also serve to introduce fuel into the combustion chamber and whereby any formation of carbon on such passages is removed by the action of the air blast.

It is a further object of this invention to provide a novel method of supplying fuel to a pot type burner whereby relatively fast and complete vaporization is obtained resulting in substantially complete and highly efficient combustion.

It is a further object of this invention to provide a modified form of liquid fuel burner in which a liquid fuel vaporizing chamber located adjacent the lower portion of the sides of the combustion chamber serves to vaporize the fuel prior to its introduction to the combustion chamber, the structure forming the vaporizing chamber also serving to prevent undesirable burning or flames outside the combustion chamber.

It is another object of this invention to provide

2

a still further modified form of liquid fuel burner in which a separate vaporizing compartment located below the combustion chamber serves to vaporize the fuel prior to its introduction to the combustion chamber through apertures in the bottom thereof.

Further objects and advantages of the invention will be apparent from the following description taken in conjunction with the accompanying drawings, wherein:

Fig. 1 is a sectional view in elevation showing the burner of this invention incorporated with a conventional fuel and forced draft supply;

Fig. 2, a partial perspective view of the burner and combustion chamber with the parts broken away for greater clarity;

Fig. 3, an elevational view in section taken on the line 3—3 of Fig. 1;

Fig. 4, a sectional view in elevation taken on the line 4—4 of Fig. 1;

Fig. 5, a partial perspective view of a modified form of the invention with parts broken away for greater clarity;

Fig. 6, an elevational view in section showing the modified burner of Fig. 5; and,

Fig. 7, a sectional view of a further modified form of the invention.

With continued reference to the drawings, there is shown in Fig. 1 a liquid fuel burner 10 secured in an aperture 11 in the top portion of an air duct 12 by rivets or other conventional fastening means 13. Air duct 12 may be formed of sheet metal or other appropriate material and is secured to a fire wall or shield 14 which may either comprise one wall of a furnace or may be utilized as a closure for an opening in a furnace through which the burner 10 is introduced for installation. Also secured to the wall 14 on the outer surface thereof is a blower 15 and a barometric type fuel supply means 16, air from the blower 15 being introduced through the duct 12 to the burner 10.

As best shown in Fig. 2, the burner 10 comprises an outer receptacle 17 having an inner bottom surface 18, upstanding side walls 19 and end walls 20. The receptacle 17 is preferably rectangular but it is within the purview of this invention that other shapes may be employed according to the particular application in which the burner is to be used.

Spaced above the upper edges 21 of the receptacle 17 is a plate 22 having a central opening 23 of the same configuration as the receptacle 17 but smaller than the internal dimensions of the receptacle. Depending from the lower surface

of the plate 22 adjacent the opening 23 are flanges 24 and 26, forming the side and end walls respectively of the combustion chamber. It is understood that if a circular burner were used, the combustion chamber would have a continuous circular wall. In the preferred form of the invention shown in Fig. 2, the opposed flanges 24 are provided with a plurality of slots 25 extending from the bottom of the flanges to a point slightly below the lower surface of the plate 22. The slots 25 provide vertical passageways extending from the inner bottom surface 18 of the receptacle 17 for the introduction of primary air to the combustion chamber formed by the opening 23 and the flanges 24. As may be seen from an inspection of Figs. 1, 3 and 4 the primary air is introduced through the duct 12 and flows between the lower surface of plate 22 and the upper edges 21 of the receptacle 17 into the space between flanges 24 and the side walls 19 of the receptacle 17 thence through the passageways 25 into the combustion chamber.

Flanges 26 which form the end walls of the combustion chamber are integral with side flanges 24 but the flanges 26 are imperforate and contact the inner bottom surface of the receptacle 17. In order to properly locate plate 22 together with its depending flanges in the receptacle 17 the bottom surface thereof may be provided with upstanding lugs 27 appropriately positioned to contact the lower inner surfaces of the flanges 24 and 26 in order to prevent movement of plate 22 and its depending flanges relative to the receptacle 17. Plate 22 and receptacle 17 are secured together by screw threaded fastening means 28 extending through apertures 29 in the plate 22 and engaging screw threaded lugs or bosses 30 formed on the outer surface of receptacle 17.

Fuel is supplied to the burner 10 through a conduit 31 from the supply 16 and is introduced to the receptacle 17 through an aperture 32 in the end wall 20 or in the case of a circular burner the aperture 32 would be located adjacent the juncture of the circular side wall with the inner bottom surface of the receptacle. Fuel thus flows through the aperture 32 and into the space 33 between the end wall 20 of the receptacle 17 and the imperforate end flange 26 depending from plate 22. From space 33 the fuel flows around the sides of flange 26 and along the space between flanges 24 and side walls 19 of the receptacle 17. Flow of the fuel from this space takes place through the lower ends of the slots 25 in flanges 24 thus introducing the fuel in a plurality of streams onto the inner bottom surface 18 within the combustion chamber formed by the flanges 24 and 26.

The above described method of introducing fuel to the combustion chamber results in a relatively thin film of the fuel flowing evenly over the bottom surface 18. Since this surface is at a relatively high temperature the fuel will be rapidly heated and will tend to vaporize almost immediately on contacting this surface. Vaporization of the fuel is further assisted and accelerated by the flow of air through the slots 25 which tends to agitate the surface of the flowing fuel; this action materially hastening vaporization.

It will thus be seen that by this structure there has been provided a means for introducing fuel to the combustion chamber of a burner over a wide area and in a relatively thin film as contrasted to prior methods of introducing fuel into

a static pool wherein heating of the fuel proceeds at a relatively slow rate and air flow thereover has little effect on vaporization resulting in the extremely low burner efficiency common in this type of burner. The burner of this invention, however, by the above described features, provides for extremely rapid vaporization, practically complete combustion and resulting burner efficiency of 20 to 30 percent higher than previous commercial pot type burners.

The efficiency of the burner is also increased by the structure which provides for the introduction of primary air in vertical streams through the slots 25 which results in a better dispersion of the fuel vapor through the air introduced into the combustion chamber, which dispersion as is commonly known in the art results in higher burner efficiency.

It is to be noted that the fuel inlet 32 is completely shielded from the combustion chamber proper by the depending flange 26 which precludes any carbon deposit forming on the fuel inlet 32 which would tend to restrict the flow of fuel therethrough. Any carbon deposit which tends to form on the edges of slots 25 is removed by the air blast passing through these slots, which further contributes to burner efficiency since the fuel flow rate is thus maintained substantially constant throughout the life of the burner. This feature also precludes the necessity for frequent cleaning of the burner.

In utilizing the principles described above in a circular or polygonal shape burner, it is contemplated that the slots 25 would extend substantially around the circumference of the depending flange with a portion thereof opposite the fuel inlet to the receptacle being imperforate in order to shield the inlet from the combustion chamber proper as described above.

This invention, in addition to the structure described above, also contemplates an improved and novel method of introducing fuel into a pot type burner in such a manner that the fuel is distributed in a relatively thin film over a comparatively large surface in order to obtain rapid and complete vaporization thereof and as a further feature this fuel is introduced through the same openings through which the primary air is introduced, thus resulting in the air flow materially assisting in the vaporization and dispersion of the fuel vapor through the air. This novel method of fuel introduction and vaporization results in very high efficiencies for this type of burner.

The modified form of the burner 10 best shown in Figs. 5 and 6 is similar in most respects to the burner above described with the exception that the receptacle 17 is provided on the inner walls thereof with an inwardly extending flange 34. The flange 34 is spaced above the bottom 18 of the receptacle 17 to provide in conjunction with side walls 19, end walls 20, flanges 24 and 26, and bottom 18 a vaporizing chamber 35. Flange 34 extends throughout the inner surface of the receptacle 17 the inner edge 34 thereof being in intimate contact with the outer walls of flanges 24 and 26 thus providing in effect a chamber extending around the entire inner surface thereof.

As above described, liquid fuel is introduced through conduit 31 and fuel inlet 32 to the space 33 between the wall 20 and depending flange 26 whereupon this fuel will flow around the ends of flange 26 and partially fill the space below the inwardly extending flange 34. Prior to ignition

of the burner the liquid fuel will of course flow from the space 35 through slots 25 into the combustion chamber but shortly after the burner is ignited sufficient heat will be produced in the bottom 18 and depending flanges 24 and 26 to completely vaporize the liquid fuel in the space 35. This results in fuel vapor rather than liquid fuel being introduced to the combustion chamber through slots 25 thus resulting in increased efficiency of the burner.

Inwardly extending flanges 34 also provide the additional functions of shielding or isolating the space thereabove between side walls 19 and depending flanges 24 from the fuel supply, thus preventing undesirable burning or flame in this space which would be dangerous and also reduce burner efficiency.

It is of course obvious that inwardly extending flange 34 may be formed integral with the walls of receptacle 17 or may be formed as a separate member and secured to the wall of this receptacle by welding or other convenient fastening means.

The principle above described in connection with the modification of Figs. 5 and 6 may also be easily applied to a conventional pot type burner comprising, as shown in Fig. 7, a combustion chamber defined by a circular or other conveniently shaped side wall 36 and a bottom 37. In the prior structures the bottom 37 was usually imperforate with liquid fuel being supplied thereto to form a static pool, the fuel vapors arising therefrom burning slightly above the surface of the pool. It was also common practice to provide the wall 36 with primary air inlets in the form of apertures 38.

In applying applicant's invention to this structure, the bottom 37 is provided with a series of apertures 39 preferably formed in a single row slightly spaced from the outer periphery of the bottom although it is of course obvious that these apertures 39 may also form other patterns rather than a single circular row. Attached to the bottom 37 adjacent the side wall 36 is a receptacle 40 forming a chamber 41 closed at the top by a bottom 37 and communicating with the combustion chamber through apertures 39. Liquid fuel is supplied to the chamber 41 by a conduit 42, the level in the chamber 41 being maintained by any convenient means such as a barometric feed.

In the operation of this form of the invention liquid fuel is supplied to the chamber 41 in sufficient quantity to flow through apertures 39 onto the bottom 37 whereupon the fuel is ignited. As soon as sufficient heat is developed in the combustion chamber this will be radiated to the chamber 41 from the bottom 37 thus vaporizing the fuel in chamber 41, the vapors then being introduced to the combustion chamber through apertures 39. This action results in the fuel supply to the combustion chamber being in the form of vapor only which of course results in a relatively high burner efficiency as compared to burner efficiency when fuel is supplied to the combustion chamber in liquid form.

It has been found in practice that sufficient heat is developed both in the form illustrated in Figs. 5 and 6 and in the form shown in Fig. 7 to vaporize the fuel in the vaporizing chamber to such an extent that vapor only is supplied to the combustion chamber, such vaporization being at a rapid enough rate to insure that no liquid fuel will flow to the combustion chamber.

The above described methods may be conveniently applied to existing pot type burners and the burners described herein incorporating these

methods may be conveniently applied to existing furnaces or may be incorporated as a built-in unit in new furnaces.

It is apparent that there is provided by this invention very simple and efficient liquid fuel burners which are economical to manufacture and in which maintenance and repair costs are kept to a minimum.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A burner for liquid fuel comprising an open top receptacle having an inner bottom surface, imperforate side and end walls, a fuel inlet in one of said end walls, a plate spaced above the upper edges of said walls, a central opening in said plate, side and end flanges depending from said plate adjacent said opening forming side and end walls defining a combustion chamber, said flanges extending downwardly in spaced relation to said side and end walls and into intimate contact with the inner bottom surface of said receptacle, relatively narrow vertical slots in said side flanges extending from the bottom thereof to points adjacent the lower surface of said plate, said end flanges being imperforate and one said flange serving to shield said fuel inlet from said combustion chamber thus preventing the formation of carbon deposits in said inlet, said fuel being introduced to said combustion chamber in a relatively thin film through the lower portions of said slots, the heated bottom surface of said receptacle together with the air flowing through said slots serving to completely vaporize said fuel thus producing substantially complete combustion thereof.

2. A burner for liquid fuel comprising an open top receptacle having an inner bottom surface, imperforate side and end walls, a fuel inlet in one of said end walls, a plate spaced above the upper edges of said walls, a central opening in said plate, side and end flanges depending from said plate adjacent said opening forming side and end walls defining a combustion chamber, said flanges extending downwardly in spaced relation to said side and end walls and into intimate contact with the inner bottom surface of said receptacle, apertures in said side flanges, said end flanges being imperforate and one said flange serving to shield said fuel inlet from said combustion chamber, thus preventing the formation of carbon deposits in said inlet, said fuel being introduced to said combustion chamber in a relatively thin film through said aperture, the heated bottom surface of said receptacle together with the air flowing through said apertures serving to completely vaporize said fuel thus producing substantially complete combustion thereof.

3. A burner for liquid fuel comprising a receptacle having a relatively flat inner bottom surface and an outer wall, a fuel inlet in said outer wall, a combustion chamber within said receptacle defined by an inner side wall extending above said outer wall the lower edge of which abuts said bottom surface, a portion of said side wall having apertures open to said bottom surface and a portion of said side wall adjacent said fuel inlet being imperforate whereby said fuel inlet is shielded from said combustion chamber thus preventing the formation of carbon deposits

in said inlet, said fuel being introduced to said combustion chamber in a relatively thin film through said apertures and an air inlet to the space between said inner and outer walls.

4. A burner for liquid fuel comprising an open top receptacle having an inner bottom surface, imperforate side and end walls, an inwardly extending flange on said side and end walls spaced above said bottom surface, a fuel inlet in one of said end walls and means to supply liquid fuel thereto, a plate spaced above the upper edges of said walls, a central opening in said plate, and end flanges depending from said plate adjacent said opening forming side and end walls defining a combustion chamber, said flanges extending downwardly in spaced relation to said side and end walls and into intimate contact with the inner bottom surface of said receptacle and with the inner edge of said inwardly extending flange, the space below said flange forming a fuel vaporizing chamber, relatively narrow vertical slots in said side flanges extending from the bottom thereof to points adjacent the lower surface of said plate, said end flanges being imperforate and one said flange serving to shield said fuel inlet from said combustion chamber thus preventing the formation of carbon deposits in said inlet, said liquid fuel upon flowing from said inlet to said vaporizing chamber being vaporized therein and the fuel vapor being introduced to said combustion chamber through the lower portions of said slots.

5. A burner for liquid fuel comprising an open top receptacle having an inner bottom surface, imperforate side and end walls, an inwardly extending flange on said side and end walls spaced above said bottom surface, a fuel inlet in one of said end walls and means to supply liquid fuel thereto, a plate spaced above the upper edges of said walls, a central opening in said plate, side and end flanges depending from said plate adjacent said opening forming side and end walls defining a combustion chamber, said flanges extending downwardly in spaced relation to said side and end walls and into intimate contact with the inner bottom surface of said receptacle and with the inner edge of said inwardly extending flange, the space below said flange forming a fuel vaporizing chamber, apertures in said side flanges, said end flanges being imperforate and one said flange serving to shield said fuel inlet from said combustion chamber thus preventing the formation of carbon deposits in said inlet, said liquid fuel upon flowing from said inlet to said vaporizing chamber being vaporized therein and the fuel vapor being introduced to said combustion chamber through said apertures.

6. A burner for liquid fuel comprising an open top receptacle having an imperforate inner bottom surface and an outer wall, an inwardly extending flange on said outer wall spaced above said bottom surface, a fuel inlet in said outer wall and means to supply liquid fuel thereto, a plate spaced above the upper edge of said wall, a central opening in said plate, a flange depending from said plate adjacent said open-

ing, said flange extending downwardly in spaced relation to said wall and into intimate contact with the inner bottom surface of said receptacle and defining a combustion chamber, the outer surface of said depending flange being in intimate contact with the inner edge of said inwardly extending flange, the space below said flange forming a fuel vaporizing chamber, relatively narrow vertical slots in said flange extending from the bottom thereof to a point adjacent the lower surface of said plate, a portion of said flange being imperforate and located adjacent said fuel inlet whereby said fuel inlet is shielded from said combustion chamber thus preventing the formation of carbon deposits in said inlet, said liquid fuel upon flowing from said inlet to said vaporizing chamber being vaporized therein and the fuel vapor being introduced to said combustion chamber through the lower portions of said slots.

7. A burner for liquid fuel comprising an open top receptacle having an imperforate inner bottom surface and an outer wall, an inwardly extending flange on said outer wall spaced above said bottom surface, a fuel inlet in said outer wall and means to supply liquid fuel thereto, a plate spaced above the upper edge of said wall, a central opening in said plate, a flange depending from said plate adjacent said opening, said flange extending downwardly in spaced relation to said wall and into intimate contact with the inner bottom surface of said receptacle and defining a combustion chamber, the outer surface of said depending flange being in intimate contact with the inner edge of said inwardly extending flange, the space below said flange forming a fuel vaporizing chamber, apertures in said flange below said inwardly extending flange, a portion of said downwardly extending flange being imperforate and located adjacent said fuel inlet whereby said fuel inlet is shielded from said combustion chamber thus preventing the formation of carbon deposits in said inlet, said liquid fuel upon flowing from said inlet to said vaporizing chamber being vaporized therein and the fuel vapor being introduced to said combustion chamber through said apertures.
